GUIDE CLAMP FOR FLUSH VALVES

Otto Stader, Ardmore, Pa.

Application October 29, 1952, Serial No. 317,455

4 Claims. (Cl. 4-57)

1

The present invention relates to new and useful improvements in guide clamps for flush valves and more particularly to new and useful improvements in adjustable guide clamps which may be positioned about and secured to overflow pipes of different diameters.

Prior to the present invention, guide clamps were provided which had a fixed internal diameter and would only fit about overflow pipes having the same diameter. If the overflow had a smaller diameter, the guide clamp would not fit properly but the clamp and clamp tightening means would engage merely a portion of the periphery of the overflow pipe and no provision has been made in prior guide clamps for flush valves to tighten the clamp about the overflow pipe to such an extent that the clamp engages the entire periphery of the overflow pipe, thereby distributing pressure and wear on the overflow pipe about its entire periphery.

With the foregoing in mind, the principal object of the present invention is to provide a novel guide clamp for flush valves which is adjustable and may be positioned about overflow pipes of varying diameters.

Another object of the present invention is to provide a novel adjustable guide clamp for flush valves which will engage the entire periphery of the overflow pipe regardless of the diameter of the overflow pipe.

A still further object of the present invention is to provide a novel guide clamp for flush valves having the features and characteristics set forth which may be manufactured easily and cheaply and is entirely efficient and effective in operation and use.

These and other objects of the present invention and the various features and details of the operation and construction thereof are herein-after more fully set forth and described with reference to the accompanying drawings, in which:

Fig. 1 is a front elevational view partially in section of a water closet having installed therein flush valve mechanism made in accordance with the present invention;

Fig. 2 is an enlarged side elevational view of the flush valve guide clamp of the present invention;

Fig. 3 is a sectional plan view of the guide clamp taken on line 3-3, Fig. 2;

Fig. 4 is a fragmentary perspective view of the forward end of the guide clamp which is fastened about the overflow pipe in the water closet;

Fig. 5 is an enlarged fragmentary sectional view

2

taken on line 5-5, Fig. 3, illustrating the method of securing the guide sleeve to the clamp member; and

Fig. 6 is a plan view of the blank from which the flush valve guide clamp is formed.

Referring more specifically to the drawings and particularly Fig. 1 thereof, the present invention is shown in conjunction with a conventional water closet, designated generally by reference numeral 10, which comprises a tank 11 having an outlet pipe 12 in the base portion thereof. The outlet pipe 12 is secured to a valve sleeve 13 in the base of the tank 11 and the sleeve 13 is provided at its upper end with an annular wall portion which serves as a valve seat for the standard resilient valve element 14. Communicating with the sleeve 13 and outlet pipe 12 is the usual overflow pipe 15 which prevents the tank 11 from overflowing. An operating lever 16 pivotally mounted on the forward face of the tank 11 and actuated by means of handle 17 controls the flow of water in the tank in the usual manner.

The valve element 14 is manufactured of a resilient material such as rubber or plastic and has a valve stem 18 extending vertically upward therefrom. A connecting link 19 secured in an opening in the operating lever 16 and having an eye portion 20 which encircles the valve stem 18, interconnects the valve stem with the operating lever to permit the valve element 14 to be removed from engagement with the valve seat upon actuation of the handle 17. This is standard type of valve and valve actuating mechanism found in the usual water closet.

In accordance with the present invention, a guide clamp 22 is provided which is secured to the overflow pipe 15 and engages the valve stem 18 in order to guide the valve element 14 into engagement with the valve seat after actuation of the operating lever 16. The guide clamp 22 is formed from a strip of material or blank as shown in Fig. 6 which is cut in two places as indicated at 23, 23 to form upper and lower straps or bands 24a, 24a and a central strap 24b of greater width than the upper and lower straps. The straps or bands are then pressed outwardly away from each other alternately at opposite sides of the blank into generally semi-circular shape so that the upper and lower straps 24a, 24a extend outwardly at one side of the clamp while the central strap projects outwardly on the opposite side of the clamp, thereby forming a generally cylindrical opening 25 which may be positioned about the overflow pipe 15. The forward end of each of the straps is reversely bent upon

itself with a relatively short radius to form a second generally cylindrical opening 26 forwardly adjacent the opening 25. The straps that form the openings 25 and 26 are joined together at both ends since the cuts or breaks 23 in the blank from which the guide clamp is formed terminate before they reach the end of the blank. By this construction, enlarging the opening 26 will cause the opening 25 to become smaller and accordingly, after the guide clamp is placed on the overflow pipe, it may be tightened therein by enlarging the opening 26. If desired, the blank may be stamped into its finished shape so that the cuts or breaks 23 in the blank and the openings 25 and 26 are formed in one operation.

An important feature of the present invention is the provision of means which may be inserted into the opening 26 in order to enlarge the opening 26 with a corresponding decrease in size of the opening 25. In the illustrated embodiment of the present invention, a tapered member 28 having screw threads thereon is provided which may be inserted into the opening 26 and rotated by means of a screw driver or other tool in order to enlarge the opening 26. The screw threads on the tapered member 28 engage the inner peripheral surface of the opening 26 and pull the tapered member 28 downwardly into the opening 26 upon clockwise rotation, thereby tightening the guide clamp 22 on the overflow pipe 15. In addition, any type of tapered pin may be used to decrease the size of the opening 25 as long as means are provided to draw or force the tapered pin into the opening 26.

The end of the blank for the guide clamp 22 opposite the openings 25 and 26 is twisted 90° as illustrated in Figs. 2 and 3 and has an opening 31 provided at its extreme end portion in which a sleeve 32 is inserted. The upper end of the sleeve 32 is peened outwardly as shown in Fig. 5 to secure the sleeve 32 in the opening 31 and maintain the axis of sleeve 32 in predetermined spaced parallel relationship with the axis of the opening 25. The sleeve 32 receives the valve stem 18 which is carried by the resilient valve 14 and acts as a guide for the valve member to insure proper seating of the valve member after operation of the flush valve.

From the foregoing, it will be observed the present invention provides a novel guide clamp for flush valves which may be secured to the usual overflow pipe and is adjustable to fit on overflow pipes of varying diameters. In addition, it will be apparent that the present invention provides a novel guide clamp for flush valves which may be manufactured easily and cheaply and is entirely efficient and effective in operation and use.

While a particular embodiment of the present invention has been illustrated and described herein, it is not intended to limit the invention to such a disclosure and changes and modifications may be incorporated and embodied therein within the scope of the following claims.

I claim:

1. A guide clamp for the stems of flush valves and like elements comprising an elongated member having oppositely displaced strap portions of substantially semi-circular configuration adjacent one end of the member disposed in confronting complementary relation to each other and defining a substantially circular first opening to receive a supporting member for the clamp, said oppositely displaced strap portions terminating at their outer ends in reversely formed smaller loop portions

70
75

formed smaller loop portions oppositely disposed with respect to each other in relatively superimposed coaxial relation and defining a second opening therethrough, and a tapered member engaged in said second opening and operable the further it enters the second opening to expand said loop portions and thereby contract the said strap portions of the member and reduce the size of the opening defined by the strap portions.

2. A guide clamp for the stems of flush valves and like elements comprising an elongated member having oppositely displaced strap portions of substantially semi-circular configuration adjacent one end of the member disposed in confronting complementary relation to each other and defining a substantially circular first opening to receive a supporting member for the clamp, said oppositely displaced strap portions terminating at their outer ends in reversely formed smaller loop portions oppositely disposed with respect to each other in relatively superimposed coaxial relation and defining a second opening therethrough having its axis parallel to the axis of the first opening, a tapered member engaged in said second opening and operable the further it enters the second opening to expand said loop portions and thereby contract the said strap portions of the member and reduce the size of the opening defined by the strap portions, and means mounted in the other end portion of the member defining an opening therein having its axis disposed in the plane of the axes of the first and second openings in the first mentioned end portion of the member.

3. A guide clamp for the stems of flush valves and like elements comprising a flat elongated member twisted intermediate its ends to dispose its opposite end portions in different planes substantially at right angles to each other, oppositely displaced strap portions of substantially semi-circular configuration in one end portion of the member disposed in confronting complementary relation to each other and defining a substantially circular first opening to receive a supporting member for the clamp, said oppositely displaced strap portions terminating at their outer ends in reversely formed smaller loop portions oppositely disposed with respect to each other in relatively superimposed coaxial relation and defining a second opening therethrough having its axis parallel to the axis of the first opening, and a tapered member engaged in said second opening and operable the further it enters the second opening to expand said loop portions and thereby contract the said strap portions of the member and reduce the size of the opening defined by the strap portions.

4. A guide clamp for the stems of flush valves and like elements comprising a flat elongated member twisted intermediate its ends to dispose its opposite end portions in different planes substantially at right angles to each other, oppositely displaced strap portions of substantially semi-circular configuration in one end portion of the member disposed in confronting complementary relation to each other and defining a substantially circular first opening to receive a supporting member for the clamp, said oppositely displaced strap portions terminating at their outer ends in reversely formed smaller loop portions oppositely disposed with respect to each other in relatively superimposed coaxial relation and defining a second opening therethrough having its axis parallel to the axis of the first opening, a tapered member engaged in said second

opening and operable the further it enters the second opening to expand said loop portions and thereby contract the said strap portions of the member and reduce the size of the opening defined by the strap portions, and a sleeve mounted in the other end portion of the member, the said sleeve having its axis disposed in the plane of the axes of the first and second openings in the first mentioned end portion of the member.
